UNITED STATES PATENT OFFICE.

DANIELL W. SYLVESTER, OF CLEMSON COLLEGE, SOUTH CAROLINA.

DESIGN FOR A BELT-BUCKLE.

49,554.

Specification for Design.

Patented Aug. 22, 1916.

Application filed June 24, 1916. Serial No. 105,732. Term of patent 3½ years.

To all whom it may concern:

Be it known that I, DANIELL W. SYLVESTER, a citizen of the United States, residing at Clemson College, in the county of Oconee and State of South Carolina, have invented a new, original, and ornamental Design for a Belt-Buckle, of which the following is a specification, reference being had to the accompanying drawing, forming part thereof.

The figure is a perspective view of a belt buckle embodying my design.

I claim:

The ornamental design for a belt buckle, as shown.

DANIELL W. SYLVESTER.

Witnesses:

E. B. ELMERER,
G. C. HIGH.
